UNITED STATES PATENT OFFICE.

GEORG SPIESS, OF LEIPZIG-REUDNITZ, GERMANY.

DEVICE FOR ACTUATING THE COUNTER IN A SHEET-FEEDER.

1,094,946.

Specification of Letters Patent. Patented Apr. 28, 1914.

Application filed January 6, 1912. Serial No. 689,746.

To all whom it may concern:

Be it known that I, GEORG SPIESS, a citizen of the Empire of Germany, and a resident of Leipzig - Reudnitz, Germany, have 5 invented certain new and useful Improvements in Devices for Actuating the Counter in a Sheet-Feeder, of which the following is a specification.

This invention relates to a novel device 10 for actuating the counting mechanism in sheet delivery apparatus.

For the purpose of counting the sheets which are passed through and delivered by the sheet delivery apparatus, the counting 15 mechanism is actuated, according to the present invention, by a swinging finger that is carried along by the edge of each passing sheet thereby causing each time a stroke in the counting mechanism. In order to attain 20 this result the suspended swinging finger is attached to a swing arm that carries a catch for the purpose of forming a movable coupling member. This catch is brought within reach of another continuously rotating coupling member by each passing sheet. The 25 swinging finger is taken along by each sheet for a certain distance and the swing arm is pushed back by the continuously rotating coupling member. While being pushed back 30 the spring arm releases intermediary elements to effect one stroke in the counter. Further means are provided for returning the operative parts into their initial positions so that a new sheet, when passing, may 35 cause another stroke in the counter.

In the accompanying drawing a device is illustrated for actuating the counting mechanism in a sheet feeder embodying in desirable form the present improvements.

40 In the form of apparatus illustrated, the finger A is suspended on the swing arm B which is movable around the pin C and adapted to swing around the shaft O. The finger is made of elastic material. Its elasticity may be adjusted by a counteracting spring D so that a passing sheet E must take 45 the swinging finger along with its front edge for a certain distance. For the purpose of forming a movable coupling member the 50 swing arm B carries on its free top end a tooth or catch F which, when at rest, is immediately before a tooth of a toothed wheel G that rotates continuously. As soon as the finger A is carried along by the sheet the 55 tooth or catch F is engaged by a tooth of

the toothed wheel G. The swing arm B and the finger A supported thereon are then forced back by the toothed wheel G whereby a detent H attached to the arm B is released from a rail or bar I which then is 60 forced upward by springs M. The bar I carries a nose K which actuates the counter. The detent H of the swing arm B has a straight bottom and a slanting top surface. The bottom surface normally rests in an incision I¹ of the bar I which forms a cam 65 surface L below its incision I¹. When a passing sheet moves the swinging finger A and places the catch F in engagement with a tooth of the continuously rotating coupling 70 member G then the detent H is released from the incision I¹ of the bar I and the springs M force the bar upward into the position shown in dotted lines. While the bar I moves upward its slanting cam surface 75 L slides along the detent H and forces the arm B to the right somewhat beyond the dotted line position lifting the finger from the passing sheet E. When the bar I is in its upmost position the detent H has passed 80 the cam surface L and slides off resting then with the top portion of its slanting top surface against the bottom end of the cam portion of the bar I. Now the arm B and parts secured thereto occupy the position shown in 85 dotted lines.

For the purpose of effecting a stroke in the counter Q the nose K of the bar I assumes a rigid position when moving upward 90 to effect a stroke but yields when moving down so as not to actuate the counter.

To return the operative parts into their initial positions the shaft of the continuously rotating coupling member G carries a cam disk P having a cam 1 and the bar I 95 is provided with a pin 2 which is adapted to be periodically engaged by the cam 1. The bar I thus is forced downward and the slanting top surface of the detent H slides around the bottom portion of the bar I 100 bringing the detent onto the cam surface L and returning it finally into the incision I¹. A spring N secured with one end to the pin C of the arm B and with the other 105 to part of the frame of the delivery apparatus is tensioned when the arm B moves to the right. It now aids in drawing the arm B with finger A into their initial positions and holds them there until a passing sheet moves the finger A again and causes re- 110

newed engagement of the catch F with the continuously rotating coupling member G, and so forth as described.

I claim as my invention:

- 5 1. A device for actuating the counter in a sheet feeder by means of the passing sheet, comprising a suspended swinging finger carried forward by the moving sheet, a catch attached to the top of the swinging finger 10 forming one member of a coupling, a continuously rotating second coupling member adapted to engage periodically the first coupling member, a counter, and means actuated by the coupling adapted to effect a 15 stroke in the counter.
2. A device for actuating the counter in a sheet feeder by means of the passing sheet, comprising an elastic suspended swinging finger, a spring bearing against said finger 20 to adjust its elasticity, a catch attached to the top of the swinging finger forming one member of a coupling, a continuously rotating second coupling member adapted to engage periodically the first coupling member, a counter, and means actuated by the coupling adapted to effect a stroke in the 25 counter.
3. A device for actuating the counter in a sheet feeder by means of the passing sheet, 30 comprising a spring operated vertical bar, a swing arm in operative connection with said bar, an elastic swinging finger on said arm adapted to be moved by a passing sheet and having a top tooth or catch forming one 35 member of a coupling, a continuously rotating coupling member adapted to be engaged by the first coupling member when the passing sheet has actuated the swinging finger thereby releasing the vertical bar, 40 a counter, and means on the bar to effect a stroke in the counter.
4. A device for actuating the counter in a sheet feeder by means of the passing sheet, comprising a spring operated vertical bar 45 having an incision in its lower portion, a swing arm in operative connection with said

bar, a swinging finger on said arm adapted to be moved by a passing sheet and having a top catch forming one member of a coupling, a detent on said swing arm resting 50 normally in the incision of the vertical bar, and a continuously rotating tooth wheel forming the second coupling member so arranged that the first coupling member is placed in location for engagement by the 55 movement of the passing sheet whereby the detent of the swing arm is released from the incision of the vertical bar.

5. In a device for actuating the counter in a sheet feeder by the movement of a passing sheet, a vertical bar having a slanting cam surface on its bottom portion and an incision at the upper end thereof, a swing arm with detent normally in said incision, and a swing finger suspended from the swing arm 65 and adapted to be actuated by the weak force of a passing sheet whereby the detent of the swing arm is moved out of the incision the vertical bar drawn up and the detent pushed to the right by the cam surface 70 of said bar.

6. A device for actuating the counter in a sheet feeder, comprising a swing arm with swing finger adapted to be moved by a passing sheet, a catch on said swing arm forming 75 a coupling member, a continuously rotating coupling member adapted to periodically engage said catch, a detent on said swing arm, a spring operated vertical bar with incision normally housing the detent 80 and having a cam surface below said incision, a counter, a nose at the top of the bar adapted to actuate the counter, and means for returning the bar and swing arm with finger into their initial positions. 85

Signed at Leipzig, Germany, this 21st day of December 1911.

GEORG SPIESS.
